WATER PISTOL

Garrison Trupp, 4600 York Road, and Bernard Trupp,
913 Lake Drive, both of Baltimore, Md.

Filed Sept. 23, 1963, Ser. No. 76,672

Term of patent 14 years

(Cl. D34—15)

FIG. 1

FIG. 3

FIG. 2

FIG. 4

FIG. 5

FIG. 8

FIG. 6

FIG. 7

FIGURE 1 is a side elevation view of a water pistol showing our new design;

FIGURE 2 is a front elevational view thereof;

FIGURE 3 is a rear elevational view thereof;

FIGURE 4 is a top plan view thereof;

FIGURE 5 is a bottom plan view thereof;

FIGURE 6 is a fragmentary side elevational view of the nozzle wherein the tip thereof is angularly disposed with straight edges in a downward direction;

FIGURE 7 is a fragmentary side elevational view of the nozzle wherein the tip is curved downwardly more sharply than FIGURE 1;

FIGURE 8 is a fragmentary side elevational view of the nozzle wherein the tip has straight edges that meet at the apex along a horizontal plane.

The side not shown is a mirror image of the side shown in FIGURE 1.

We claim:

The ornamental design for a water pistol, as shown and described.
